BARBECUE GRILL AND OVEN UNIT AND STAND THEREFOR

Charles D. Dushek, Lisle, Ill., assignor to Sears,
Roebuck and Co., Chicago, Ill.

Filed May 19, 1971, Ser. No. 145,121

Term of patent 14 years

Int. Cl. D7—02

U.S. Cl. D81—10 E

Fig. 5

FIG. 1 is a front perspective view of the barbecue grill and oven unit and stand therefor with the grill-oven housing closed; and,

FIG. 2 is a front elevation view thereof.

FIG. 3 is a side elevation of my design, the opposite side being a mirror image of the side shown;

FIG. 4 is a fragmentary side elevation view of the barbecue grill-oven with said grill-oven housing open; and

FIG. 5 is a rear elevation view of the barbecue grill and oven unit and stand therefor.

I claim:

The ornamental design for a barbecue grill and oven unit and stand therefor, as shown and described.
